UNITED STATES PATENT OFFICE.

GILBERT W. GOODRIDGE, OF FAIRFIELD, CONNECTICUT, ASSIGNOR TO THE BEAD CHAIN MANUFACTURING COMPANY, OF BRIDGEPORT, CONNECTICUT, A CORPORATION OF CONNECTICUT.

METHOD OF WIRING CONTACT PINS.

Application filed October 6, 1925. Serial No. 60,898.

My invention relates to method of wiring contact pins.

In electric fittings of various types, such as audions, lamps, etc., contact pins are secured to the insulating base of the fitting and lead wires are permanently soldered to the pins. The common practice heretofore has been to employ pins formed from rod stock, cut to length and bored to receive the lead wire.

The lead wire which is carried down through the central bore of the pin, is commonly secured at the contact end of the latter by externally applied solder. Adherent solder, however, so enlarges the pin end that a further operation upon the contact is necessary to remove the excess solder and thus maintain the pin's diameter with approximate exactitude. The necessity for approximate exactness of diameter will be appreciated when it is considered that the pins of an audion bulb base, for instance, differ in diameter, and that the holes in a cooperating receptacle through which the pins pass to engage the receptacle terminals, are accurately calibrated to insure the proper polarity position of the audion in the receptacle.

My invention provides a method of wiring which obviates the difficulties mentioned.

In the accompanying drawings—

Figs. 1 to 5 inclusive illustrate my method of connecting lead wires to the contact pins.

While my invention, in some aspects, is applicable to pins of other type than that illustrated in the accompanying drawings, the sheet metal pin shown is desirable by reason of its economy. Pins of this general type form the subject matter of the copending applications of William J. Gagnon, Ser. Nos. 56,291 and 56,292, filed September 14, 1925.

I have illustrated my invention in connection with an audion base; but it will be realized that its utility is not confined to this particular type of fitting.

As here shown, the audion comprises a glass base 15 carried by a surrounding metal shell 16, which supports the usual bulb 17. Lead wires 18 from the usual grid, filament and plate elements (not shown) pass through the lower end of the bulb and enter corresponding contact pins 19, the heads 20 of which are embedded in the glass base. At

the contact ends of the pins, the lead wires are secured by solder 21.

As pointed out in the Gagnon applications above referred to, the pins are shaped from sheet metal stock and are longitudinally split from end to end. The embedded head 20 exceeds the pin shank in diameter, and is also preferably non-circular, at least in part, as at 22, in order to hold the pin against rotation in the base.

The base, with the pins thus embedded therein, is now ready for the reception of the lead wires from the bulb. Instead of following the usual practice, however, of passing the lead wires through the pins and connecting by externally applied solder, I effect the soldered connection within the pin. A bath 32, which is pasty at normal temperature, is heated to fluid condition. The ends of the wire leads 18 of the bulb are momentarily dipped, say to the depth of 1/2", into the flux bath. After the adherent flux has congealed upon the lead wires, the latter are passed into the several pins 19 on the base. As the fluxed ends of the wires pass through the exit holes 33 at the rounded contact ends of the pins, more or less of the flux is scraped off at the holes 33 and gathered against the inner surfaces of the pins. The projecting ends of the wires may then be snipped off.

Thus assembled and prepared, the contact ends of the pins are dipped for a moment in a bath of hot solder 34. The affinity of the latter for the flux causes it to enter the hollow pins through the end apertures 33 thereof. The heat from the solder spatters the flux against the surrounding inner surfaces of the pin wall and a solid connection between the solder, lead wire and pin is thus established within the contact end of the pin. The absence of flux from the outer surface of the pin, coupled with the high temperature of the solder bath, prevents adhesion of the solder to the exterior of the pin in any substantial quantity. The pin may be slightly silvered by the solder, but no quantity sufficient to necessitate removal is deposited thereon.

While my improved method of securing the lead wires is preferably employed with pins of the sheet metal type disclosed in the Gagnon applications mentioned, it is obviously possible to employ my methods with

pins of other constructions. My method of attaching the lead wires to the pin can be employed with pins of various constructions. It will also be understood that while I have described my invention with particular reference to an audion bulb, my invention may be used on other electrical fittings to advantage.

With the understanding therefore that the foregoing description is merely illustrative of the thoughts which underlie my invention, I claim—

1. The method of connecting a lead wire to a hollow pin having at its contact end an opening of less diameter than the internal diameter of the pin, which comprises coat-

ing an end of the lead wire with flux, passing said end through the pin until its fluxed end is extended through said end opening and portion of the flux is scraped off within the pin, and dipping said end of the pin in hot solder.

2. An electric fitting having a hollow contact pin with an end opening of less diameter than the interior diameter of the contact pin, a lead wire positioned within the contact pin, and solder sealing said end opening and uniting the wire and pin within the shank of the pin.

In testimony whereof I have signed my name to this specification.

GILBERT W. GOODRIDGE.
